U.S. Appl. No. 13/801,300, filed Mar. 13, 2013, Reiss et al.

Primary Examiner — Susan Moon Lee

(74) Attorney, Agent, or Firm — Sheridan Ross PC

(57) **CLAIM**

The ornamental design for a pet toy treat dispenser, as shown and described.

DESCRIPTION

FIG. 1 is a perspective view of the pet toy treat dispenser;
 FIG. 2 is a top plan view of FIG. 1;
 FIG. 3 is a front elevation view of FIG. 1;
 FIG. 4 is a right side elevation view of FIG. 1;
 FIG. 5 is left side elevation view of FIG. 1;
 FIG. 6 is a rear elevation of FIG. 1; and,
 FIG. 7 is a bottom plan view of FIG. 1.
